DESIGN FOR A COMBINED DEMONSTRATING AND DISPLAY CASE UNIT FOR AN ELEC- TRIC RAZOR OR THE LIKE

George T. Scharfenberg, Chicago, Ill., assignor to
Chicago Flexible Shaft Company, Chicago, Ill.,
a corporation of Illinois

Application August 1, 1940, Serial No. 94,114

Term of patent 7 years

To all whom it may concern:

Be it known that I, George T. Scharfenberg, a citizen of the United States, residing at Chicago, in the county of Cook and State of Illinois, have invented a new, original, and ornamental Design for a Combined Demonstrating and Display Case Unit for an Electric Razor or the like, of which the following is a specification, reference being had to the accompanying drawing, forming part thereof.

In the drawing:

Fig. 1 is a side elevational view of a combined demonstrating and display case unit for an electric razor or the like, showing my new design;

Fig. 2 is a top plan view; and

Fig. 3 is a front elevational view.

I claim:

The ornamental design for a combined demonstrating and display case unit for an electric razor or the like, substantially as shown.

GEORGE T. SCHARFENBERG.
